US0D1091042S

(12) **United States Design Patent** (10) **Patent No.:** **US D1,091,042 S**
(45) **Date of Patent:** **** Aug. 26, 2025**

(54) **DUSTBIN**

(71) Applicant: **Swanlord (Shanghai) Houseware Limited**, Shanghai (CN)

(72) Inventor: **Huanbang Lu**, Shanghai (CN)

(73) Assignee: **Swanlord (Shanghai) Houseware Limited**, Shanghai (CN)

(**) Term: **15 Years**

(21) Appl. No.: **29/940,977**

(22) Filed: **May 7, 2024**

(30) **Foreign Application Priority Data**

Mar. 6, 2024 (CN) 202430112552.6

(51) **LOC (15) Cl.** **09-09**

(52) **U.S. Cl.**

(57) **CLAIM**

The ornamental design for a dustbin, as shown and described.

DESCRIPTION

FIG. 1 is a top, front, right-side perspective view of a dustbin showing my new design;

FIG. 2 is a bottom, front, left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings depict portions of the dustbin and form no part of the claimed design.

1 Claim, 8 Drawing Sheets
